UNITED STATES PATENT OFFICE.

EUGÈNE FREYSSINET, OF PARIS, FRANCE, ASSIGNOR TO SOCIETE DES NAVIRES EN CIMENT ARMÉ, OF PARIS, FRANCE.

METHOD OF MOLDING CONCRETE SHIPS.

1,349,826.

Specification of Letters Patent. Patented Aug. 17, 1920.

Application filed June 12, 1918. Serial No. 239,587.

To all whom it may concern:

Be it known that I, EUGÈNE FREYSSINET, a citizen of the Republic of France, residing in Paris, France, have invented certain new 5 and useful Improvements in Methods of Molding Concrete Ships, of which the following is a specification.

In specification Serial No. 239,443; filed June 11, 1918 there has been described a 10 process for constructing ships and like vessels of reinforced concrete in which cellular walls are cast homogeneously, it being possible by the process to form the cells in series by any method of working while at the 15 same time securing a high degree of resistance and uniformity and a durable impermeability after formation.

The present invention relates to modified methods of making constructions having 20 similar properties and presenting some further advantages owing to the particular arrangements adopted.

According to the invention the sides of the hull are formed of two walls spaced a certain distance apart and connected by transverse beams placed in position prior to the pouring of the walls, said beams forming a skeleton on which the walls are constructed. The external and internal walls which constitute the outside and inside planking, as well as the bottom of the vessel, and the deck, the construction of which does not present any peculiarity, are advantageously constituted by surfaces having a continuous metallic skeleton comprising elements of great length which, if necessary, may carry loops *f*, such as have been described in specification Serial No. 238,579, filed June 6, 1918.

For constructing and casting at one operation each of the walls, the beams, cast as a preliminary operation and having on their edges suitable scarfings, are suspended from the framing and to the scarfings are applied metallic skeletons, such as those about to be indicated, of the inner and outer plannings. In this manner the outer wall will have the feature known to be an essential for this kind of work in naval construction, namely a continuous surface, even if the 50 beams present irregularities.

When the reinforcement or skeleton has thus been constructed light molding boards are attached thereto and to the beams, and the casting or pouring operation is then conducted with a concrete or any other suitable

mixture. Said molding boards being attached to the skeleton have no connection with the ground, and hence are free to assume the shape of the skeleton.

The accompanying drawings are given by 60 way of example to illustrate the invention.

Figure 1 is a diagrammatic cross section through a ship in the process of construction and of the framing which supports it.

Figs. 2 and 3 illustrate the construction of 65 the beams.

Fig. 4 is a vertical section through a side of the hull showing the reinforcement of the two walls and showing the molding boards for the casting operation.

Fig. 5 is a plan.

In this instance, the side walls have the cellular structure referred to, and the bottom and the deck are formed solely by prolongations of the external wall. It is obvious however that the inner wall could be extended either across the bottom or to the 70 deck of the ship.

As shown in Fig. 1, the beams *A* are suspended from a framing *B*, for the purpose 80 of putting in position the metallic skeletons of the inner and outer walls, and are connected at their lower part by beams *C* to complete the skeleton of the ship. The beams are suspended at their upper ends by 85 devices of adjustable length so that the beams can easily be brought into exact position; to prevent them from being displaced they may be connected together by any provisional system of tie rods.

The first operation in the method of construction consists in the manufacture of the beams. For making them rapidly in series while at the same time facilitating the formation of the metallic scarfings required at 95 their edges, the following simple method has been adopted:

The beam is made on a flat floor, such as is represented at *a* in Fig. 2, and Fig. 2 being a vertical section of the arrangement, 100 and Fig. 3 being a plan. To make the mold for the concrete, planks or boards *b* are fixed on the floor, the space between them having the required shape of the beam; the thickness of the planks corresponds with 105 the distance which is to be maintained between the reinforcing members and the external surface of the concrete.

On the planks *b* are then placed distance or spacing pieces *c* fastened to the planks 110

and of thickness equal to that of the reinforcing rods. These distance pieces serve to keep in place the first transverse elements *d* of the reinforcement which are placed in a direction perpendicular to the general direction of the beam and extend beyond the planks *b* between the distance pieces *e*.

The first grill of reinforcing wires having been constructed, planks *e*, of the same form as the planks *b*, are superimposed upon the latter; the thickness of these planks *e* is equal to the distance to be maintained between two reinforcing grills. Within the framing *e* thus formed there are arranged the longitudinal reinforcing members *f* extending also beyond the framing and resting on the members *d*. Next there are placed on the planks *e*, a second series of transverse reinforcing members *h* and longitudinal reinforcing rods *i* identical with those of the first series.

If the thickness of the beam is to be limited to the four sets of reinforcing rods thus brought into position, and this is the general case, the molding is finished by planks *j* identical with *b* and is then filled with concrete or other material selected.

The casting or pouring can be performed without difficulty, since the distance pieces fill up the spaces between the members *d* and *h* in the same layer. When the operation is completed the planks *b e j* are easily lifted away by slightly bending the ends of the members *d* and *h*.

All the beams *A* having been suspended as described above, and connected by the beams *C*, the whole forms a skeleton reproducing exactly the form of the hull to be constructed and completely accessible over its whole surface; it is now a simple operation to put into position the rods or members constituting the reinforcement of the walls.

The reinforcement of the outer wall of the whole hull and of the bottom is first constructed by applying metal grills or networks previously made with continuous elements, as has been described in specification Serial No. 238,579.

By reason of the continuity of the elements of the reinforcements and of the mobility of the framing formed by the suspended beams, these networks or grills will acquire a uniform curvature. It will therefore not be necessary to make the beams *A* with precision thus considerably simplifying the work of designing. The networks or grills are connected with the scarfings of the beams as indicated in Figs. 4 and 5. In these figures *E* is a part of the outer wall; the extensions *d*, *h* of the reinforcing elements of the beam *A* are bent at the part where they pass between the vertical rods *k* so as to engage beneath the longitudinal rods or elements *l*.

In this manner, the grills, such as that in the wall *E*, are fixed in place without supports or special framing.

This operation having been completed the mold in which the wall is to be cast in a single operation, is constructed and exactly connected with the scarfings of the beams.

At the bottom the mold will be supported by props *D* of ordinary form.

For the outer wall, the mold is constructed of planks *m* supported by pieces of iron or wood *n* attached to the reinforcement by connecting wires or bars, such as *o*, so as to be at a distance from the reinforcement equal to the thickness of the concrete which is to be cast between the reinforcement and the surface, plus the thickness of the planks *m*.

If the consistency of the material that is poured or cast permits, only one mold on one of the faces is necessary. When the material is poured, the operation is started at the bottom and then continued at the outer wall.

When the operation is complete the reinforcement of the internal wall *F* is then constructed and connected in manner similar to that already described for the external wall with the reinforcing elements of the beams and of the bottom by means of scarfings provided for the purpose.

The beams *C*, which were used for keeping the beams *A* in proper position are now useless and may be removed. The casting of the internal wall is an operation similar to that described for the external wall. Finally, the reinforcement of the deck is constructed and the deck is cast, care being taken to leave manholes permitting access to each cell bound by neighboring beams the internal wall and the external wall.

When the ship is finished it may be turned about a point on its keel so as to give it the inclination necessary for launching. This operation of pivoting, for which, however, may be substituted any other method of inclining the ship, is made possible by reason of the great rigidity conferred on the whole by the mode of construction.

It will be seen that the process has in addition to the facility of construction and the high degree of forced work to which it lends itself, great advantage in respect of simplicity over the processes heretofore used. Among others, one may note a total omission of scaffolding for supporting the mold and the possibility of using existing framing for several ships; finally, the easy mode of obtaining continuous forms for the keel because of the possibility of inherently obtaining continuous surfaces.

Another very important advantage is that the two walls are very easily constructed substantially parallel and are very firmly

connected together forming a solid whole of very large radius, able to resist very great crushing forces in various directions.

The foregoing details are given solely by way of example and can be modified to suit the particular circumstances without varying the essential features of the invention.

What is claimed is:—

- 10 1. A process for manufacturing reinforced concrete boats, consisting in constructing beams having reinforcing rods with projecting ends, suspending said beams from a framework in such manner that said frames may be capable of conforming movements, attaching to the outer sides of said beams continuous reinforcements going from one end to the other of the boat in the longitudinal direction, then on the interior sides of said beams applying similar reinforcements, bending in the ends of the rods projecting from the beams upon the reinforcements of the exterior and interior walls, attaching upon the reinforcements of said interior and exterior walls, exteriorly and interiorly a form or mold taking the form of the said reinforcements, simultaneously pouring cement in the several molds or forms, and removing the molds or forms.

2. A process for manufacturing reinforced concrete boats, consisting in constructing beams having reinforcing rods with projecting ends, suspending said beams from a framework in such manner that said frames may be capable of conforming movements, attaching to the outer sides of said beams continuous reinforcements going from one end to the other of the boat in the longitudinal direction, then on the interior sides of said beams applying similar reinforcements, bending in the ends of the rods projecting from the beams upon the reinforcements of the exterior and interior walls, attaching upon the reinforcements of said interior and exterior walls, exteriorly and interiorly a flexible form or mold taking the form of the said reinforcements, simultaneously pouring cement in the several molds or forms, and removing the molds or forms.

In witness whereof I have hereunto signed my name in the presence of two subscribing witnesses.

EUGÈNE FREYSSINET.
